CONVERTIBLE RIGHT AND LEFT HANDED SCISSORS

Filed Aug. 8, 1931

INVENTOR.

Quincy W. Hershey
BY O.B. Buchanan
ATTORNEY

UNITED STATES PATENT OFFICE

QUINCY W. HERSHEY, OF PITTSBURGH, PENNSYLVANIA

CONVERTIBLE RIGHT- AND LEFT-HANDED SCISSORS

Application filed August 8, 1931. Serial No. 555,953.

My invention relates to reversible, finger-and-thumb-operated scissors, shears, cigar clippers, or the like, which I shall designate by the generic term "scissors", and it has particular relation to "scissors" which are reversible in such manner as to be suited for convenient operation by either the right hand or the left hand.

Scissors are normally constructed with two blades, each with one cutting edge. These blades are known as the "finger blade" and the "thumb blade", and are manipulated by a finger or fingers and the thumb, respectively. The finger blade is provided, for this purpose, with a finger-hole or "eye", and the thumb blade is provided with a thumb hole or "eye".

The ordinary right-hand scissors have "eyes" of such shape as to facilitate the normal act of closing the thumb and fingers of the right hand, which forces the cutting edges together, the thumb blade being toward the mesial plane of the user. When such scissors are held in the left hand, however, not only do the thumb and finger eyes not fit the anatomy of the left hand, but the finger blade, rather than the thumb blade, is toward the mesial plane of the user, so that the normal act of bringing the thumb and fingers together tends to force the cutting edges apart, causing difficulty in cutting.

According to my invention, certain changes have been made in the normal design of scissors, and the blades have been made reversible in such manner that the scissors may be comfortably, efficiently and conveniently operated with either hand, thereby avoiding the difficulties hereinabove pointed out, all as will be subsequently described and claimed with reference to the accompanying drawings, wherein

Fig. 1 is an exploded plan view of a pair of scissors embodying my invention in a preferred form, with the two blades separated,

Fig. 2 is a sectional view on a plane indicated by the line II-II in Fig. 1,

Fig. 3 is a front elevational view of the scissors shown in Fig. 1, the same being assembled for use with the right hand,

Fig. 4 is an end elevational view of the scissors shown in Fig. 3,

Fig. 5 is an enlarged sectional view through the pivot pin, as indicated by the section-line V-V in Fig. 3,

Figs. 6, 7 and 8 are views, corresponding to Figs. 3, 4 and 5, respectively, but showing my scissors assembled for use with the left hand, and

Figs. 9 and 10 are enlarged sectional views illustrating modifications.

My scissors have a finger blade 11 and a thumb blade 12, pivotally joined by a pivot pin 13, and all of these parts are of abnormal design.

The blade part of the finger blade 11, as well as the part near the pivot, is of thin triangular section, as shown in Figs. 2, 5 and 8, so as to form a single cutting edge 14 (at the bottom), which is effective when the other blade (or thumb blade) 12 is disposed against either of the flat side surfaces 15 or 16 of the finger blade which is now being described.

This finger blade 11 also has a finger hole or eye 17 which is shaped to receive one or several fingers, preferably several fingers, as shown in Figs. 3 and 6, and the hole through this finger eye is preferably inclined from both sides, to fit the fingers of either hand, which is readily accomplished because of the extra thickness of the finger eye, as shown in Figs. 1, 4 and 7. The finger eye 17 is dropped down lower than usual, in the vertical plane, as shown in Figs. 3 and 6, for a purpose which will be subsequently explained.

The blade part of the thumb blade 12 is substantially triangular in section, or it may be, and preferably is, trapezoidal in section, as shown in Fig. 2. The essential thing is that it shall have two cutting edges 18 and 19, and a single operative surface 20 which may be disposed against either one of the two operative surfaces 15 or 16 of the aforementioned finger blade 11. The thumb blade is sharpened on both its top and bottom edges 18 and 19, and when I designate it as having a substantially trapezoidal section I intend to indicate this construction, even though the section may be more nearly triangular than trapezoidal.

The portion of the thumb blade 12 near the hinge pin 13 is preferably of substantially 5 or more nearly rectangular section, having a wide flattened portion to receive the head of the pivot pin, as indicated in Figs. 5 and 8, and, for convenience of reference, I shall designate the end which merges into the cutting-edge 18 by the numeral 18' and the edge which merges into the cutting-edge 19 by the 10 numeral 19'.

The thumb blade 12 has a thumb hole or eye 21 which is shaped to smoothly fit the thumb, the hole through it being properly inclined, in accordance with the normal position of the thumb, somewhat as usual, but it is disposed substantially centered with respect to the median horizontal plane of the blade-portion of the thumb blade 12, as indicated by the center-line 22 in Figs. 3 and 6.

20 The pivot pin 13 makes a detachable pivotal connection of the thumb blade 12 on either side of the finger blade 11, with the same surface 20 of the thumb blade flat against the finger blade, in either event. In 25 the embodiment of my invention shown in Figs. 1 to 8, the pivot pin 13 is carried by the finger blade 11 and extends out, on both sides of the blade, at right angles to its respective operative surfaces 15 and 16, as indicated at 25 and 26, respectively, in Figs. 4, 30 5, 7 and 8, the pin being bent for this purpose. Each of the pin-extensions 25 and 26 has a narrow oblong head 27 which normally 35 holds the thumb blade 12 in place against the finger blade 11. The thumb blade 12, however, has a pivot-hole having oblong enlargements 28 (Fig. 3) through which the narrow oblong head 27 of the bent pin 13 may pass 40 when the scissors are opened wide with the blades at substantially right angles. It will be understood, of course, that the pivot-heads 45 27 may be, and ordinarily would be, countersunk in the thumb blade 12, so as to occupy no additional space, but such countersinking has been omitted, in the illustration, in the interests of clearness.

In operation, the thumb blade 12 may be assembled with its single operative surface 20 against the front surface 15 of the finger 50 blade 11, as shown in Figs. 3 to 5, in which case a pair of right-hand scissors is formed, with the cutting edges 14 and 18 in use. Or the thumb blade 12 may be removed and replaced with its single operative surface 20 55 against the back surface 16 of the finger blade 11, as shown in Figs. 6 to 8, in which case a pair of left-hand scissors is formed, with the cutting edges 14 and 19 in use.

By reason of the center-line position of the 60 thumb eye 21, this member extends substantially the same distance below the center-line 22 in either position of the thumb blade. When the scissors are converted from right-hand to left-hand adjustment, the thumb 65 blade is simply rotated about 180° around its

center-line 22, and moved from the front surface 15 to the back surface 16 of the finger blade 11. The downward drop of the finger eye 17 is such as to accommodate this thumb eye, which abuts against the top of the finger eye, as indicated at either 30 or 31 in Figs. 4 and 7, thus limiting the closing movement of the scissors. The rotation of the thumb blade about its center-line also reverses the inclination of the hole through the thumb eye 75 21, as will be seen by a comparison of Figs. 4 and 7, so that the thumb of the other hand may comfortably be thrust therein, with the inclination of the hole proper also for causing the operative surfaces of the cutting portions of the blades to be pressed closely together.

The essential requirement of the pivot-connection 13 is that it shall detachably hold 80 the two blades together with the single operative surface 20 of the thumb blade 12 held flat against either one of the two operative surfaces 15 or 16 of the finger blade 11. Any form of pivotal attachment that 85 accomplishes this purpose may be utilized. 90

Thus, as indicated in Fig. 9, the pivot pin 33 may be carried by the thumb blade 12a, in which case it extends on only one side, and is straight instead of being bent. It is perpendicular to the single operative surface 20a of the thumb blade 12a, and extends into a double-frusto-conical aperture 34 in the finger blade 11a, said aperture having enlargements (not shown) similar to the 100 enlargements 28 of Fig. 3 for receiving the narrow head 35 of Fig. 9. The frusto-conical aperture 34 permits the pin 33 to enter, from either side, at right angles to the surface, 15a or 16a, through which it enters.

Fig. 10 shows a still further modification 105 of the pivot-pin connection wherein the triangular-sectioned blade 11b has a large hole 37 for receiving a pin 38 having a headed portion 39 of large cross-section removably fitting in said hole 37, which is perpendicular to the vertical center-line 40 of the triangular section. The head 41 of the large pin-section 39 is inclined, so as to rest against the lateral face 42 of the triangular-sectioned 110 blade. The pin also has a reduced portion 43 of smaller circular section and at an angle to the axis of the large section 39, said reduced portion terminating in a narrow head-portion 44, at right angles thereto, which lies within the confines of an extension of the lateral surface of said large section, as indicated by dotted lines 45. The trapezoidal-sectioned blade 12b has a pivot hole 46 for accommodating said reduced pin-section 43 and having an enlargement 28, as shown in Fig. 3, through which the narrow head-portion 44 may be removed when the 115 scissors are opened, as previously described.

When the trapezoidal-sectioned blade 12b of Fig. 10 is removed, the entire pin 38 may 120

be backed out through the hole 37 in the triangular-sectioned blade 11b, and it may then be replaced from the other side, as will be obvious. The hole 37 and its fitting pin 5 part 39 are preferably non-circular in section, so as to force the pin to be put in in the proper position. The pin 38 preferably has a spring-washer 47 encircling the large pin-section 39 next to its head 41 and preferably permanently attached thereto, as by having a tab 42 bent down into a notch 43 in the pin, as shown in Fig. 10.

In the foregoing specification, as well as in the appended claims, when I speak of the finger blade 11 having a single cutting edge 14, I mean that the bottom edge of each of the operative surfaces 15 and 16 constitutes a cutting edge, and that these cutting edges are close together, if not exactly geometrically perfectly coincident.

The herein-described and illustrated embodiments of my invention are given by way of example, to set forth the principles thereof. I intend that the appended claims shall 25 be broadly construed, in accordance with the state of the prior art.

I claim as my invention:

1. Convertible right- and left-hand scissors comprising a finger blade having a single cutting edge and two operative surfaces, a thumb blade having two cutting edges and a single operative surface, and pivot-means for detachably holding the two blades together with the single operative surface of 30 the thumb blade held flat against either one of the two operative surfaces of the finger blade.

2. The invention as specified in claim 1, characterized by said pivot-means comprising a bent pivot-pin carried by the finger blade to provide two extensions perpendicular to said two operative surfaces of said finger blade.

3. The invention as specified in claim 1, characterized by said pivot-means comprising a pivot-pin carried by said thumb blade at substantially right angles to its operative surface, the finger blade having a pivot-aperture of substantially double-frusto-conical shape.

4. The invention as specified in claim 1, characterized by the thumb blade having a thumb eye substantially centered with respect to the center-line through its blade-portion, the finger blade having a finger eye suitably depressed to accommodate the thumb eye in either position of the thumb blade.

5. The invention as specified in claim 1, characterized by the thumb blade having a thumb eye substantially centered with respect to the center-line through its blade-portion, the finger blade having a finger eye suitably depressed to accommodate the thumb eye in either position of the thumb blade, said finger eye being larger than said thumb

eye, and both of said eyes having holes which are inclined and shaped to comfortably fit the anatomy of the hand in the intended use of the scissors.

6. The invention as specified in claim 1, characterized by the thumb blade having a thumb eye substantially centered with respect to the center-line through its blade-portion, the finger blade having a finger eye suitably depressed to accommodate the thumb eye in either position of the thumb blade, the thumb eye having a hole which is inclined in a single direction, so that, by reversing the thumb blade, it is made to fit the inclination of either thumb and will help to hold the cutting edges together in either case. 70

7. The invention as specified in claim 1, characterized by the thumb blade having a thumb eye substantially centered with respect to the center-line through its blade-portion, the finger blade having a finger eye suitably depressed to accommodate the thumb eye in either position of the thumb blade, the thumb eye having a hole which is inclined in a single direction, so that, by reversing the thumb blade, it is made to fit the inclination of either thumb and will help to hold the cutting edges together in either case. 80

8. The invention as specified in claim 1, characterized by the thumb blade having a thumb eye substantially centered with respect to the center-line through its blade-portion, the finger blade having a finger eye suitably depressed to accommodate the thumb eye in either position of the thumb blade, the thumb eye having a hole which is inclined in a single direction, so that, by reversing the thumb blade, it is made to fit the inclination of either thumb and will help to hold the cutting edges together in either case, and the finger eye being thicker than the thumb eye and having a doubly inclined hole to accommodate the finger-position of either hand. 85

9. Convertible right- and left-hand scissors having a finger blade with a substantially triangular cross-section and a thumb blade with a substantially trapezoidal cross-section. 90

10. Convertible right- and left-hand scissors having a finger blade with a substantially triangular cross-section and a thumb blade with a substantially trapezoidal cross-section and pivot-means for detachably holding the two blades together with the wide surface of the trapezoidal-sectioned blade held flat against one or the other of the two side surfaces of the triangular-sectioned blade. 100

11. Convertible right- and left-hand scissors comprising a finger blade having two operative surfaces, a thumb blade having a single operative surface sharpened at both its top edge and its bottom edge, and pivot-means for detachably holding the two blades together with the single operative surface of the thumb blade held flat against either one of the two operative surfaces of the finger blade, the thumb blade having a thumb eye substantially centered with respect to the center-line through its blade-portion. 110

12. Convertible right- and left-hand scissors comprising a finger blade having two operative surfaces, a thumb blade having a single operative surface sharpened at both its top edge and its bottom edge, and pivot-means for detachably holding the two blades together with the single operative surface of the thumb blade held flat against either one of the two operative surfaces of the finger blade. 115

13. Convertible right- and left-hand scissors comprising a finger blade having two operative surfaces, a thumb blade having a single operative surface sharpened at both its top edge and its bottom edge, and pivot-means for detachably holding the two blades together with the single operative surface of the thumb blade held flat against either one of the two operative surfaces of the finger blade. 120

14. Convertible right- and left-hand scissors comprising a finger blade having two operative surfaces, a thumb blade having a single operative surface sharpened at both its top edge and its bottom edge, and pivot-means for detachably holding the two blades together with the single operative surface of the thumb blade held flat against either one of the two operative surfaces of the finger blade. 125

15. Convertible right- and left-hand scissors comprising a finger blade having two operative surfaces, a thumb blade having a single operative surface sharpened at both its top edge and its bottom edge, and pivot-means for detachably holding the two blades together with the single operative surface of the thumb blade held flat against either one of the two operative surfaces of the finger blade. 130

blade, the thumb blade having a thumb eye substantially centered with respect to the center-line through its blade-portion, the finger blade having a finger eye suitably depressed to accommodate the thumb eye in either position of the thumb blade and providing a stop for the thumb blade in the closed position of the scissors.

12. Scissors comprising a finger blade having two operative surfaces, a thumb blade, and pivot-means for detachably holding the two blades together with the thumb blade held, at will, flat against either operative surface of the finger blade.

13. The invention as specified in claim 12, characterized by one blade having a pivot pin having a narrow elongated head, the other blade having a pin-aperture having an enlargement for receiving said head when the scissors are opened wide.

14. Scissors comprising a finger blade, a thumb blade and a pivot-means therefor, said finger blade having a substantially triangular cross-section throughout the length of its cutting portion and portion near the pivot-means and having a single cutting edge at the apex of said triangular section, said pivot-means being operative to hold the thumb blade against either side of said triangular section forming the cutting edge.

15. Convertible right- and left-hand scissors comprising two blades detachably pivoted together, characterized by one of said blades having a substantially triangular cross-section, and the other of said blades being reversible around a longitudinal line, and disposable on opposite sides of the first-mentioned blade.

16. Convertible right- and left-hand scissors comprising two blades detachably pivoted together, characterized by one of said blades having a substantially triangular cross-section, and the other of said blades being reversible around a longitudinal line, and disposable on opposite sides of the first-mentioned blade, and further characterized by one of said blades having an eye which is substantially centered with respect to the median horizontal plane of its blade-portion, the other blade having an eye which is suitably dropped to make room for the first-mentioned eye.

17. Convertible right- and left-hand scissors comprising two blades detachably pivoted together, characterized by one of said blades having a substantially triangular cross-section, and the other of said blades being reversible around a longitudinal line, and disposable on opposite sides of the first-mentioned blade, the reversible blade having an eye which is substantially centered with respect to the median horizontal plane of its blade-portion, the other blade having an eye which is suitably dropped to make room for the first-mentioned eye.

18. Convertible right- and left-hand scissors comprising two blades detachably pivoted together, characterized by one of said blades having a substantially triangular cross-section, and the other of said blades being reversible around a longitudinal line, and disposable on opposite sides of the first-mentioned blade, the reversible blade having an eye which is substantially centered with respect to the median horizontal plane of its blade-portion, the other blade having an eye which is suitably dropped to make room for the first-mentioned eye, and further characterized by the substantially centered eye having a hole of a single inclination, and the other eye having a doubly inclined hole.

19. Reversible scissors comprising a substantially triangular-sectioned blade, a substantially trapezoidal-sectioned blade adapted to be pivoted thereto with its large flat side against either one of the two lateral surfaces of the triangular-sectioned blade, and a self-locking reversible pivot pin for detachably joining said two blades, comprising a headed portion having a large cross-section removably fitting in a hole in the triangular-sectioned blade, the head on said portion being inclined, and a reduced portion of smaller circular section and at an angle to the axis of the large section, said reduced portion terminating in a narrow head-portion, at right angles thereto, which lies within the confines of an extension of the lateral surface of said large section, the trapezoidal-sectioned blade having a pivot-hole for accommodating said reduced pin-section and having an enlargement for receiving said narrow head-portion.

20. The invention as specified in claim 19, characterized by a spring washer non-removably secured to said large pin-section next to its head.

In testimony whereof, I have hereunto subscribed my name this 4th day of August, 1931.

QUINCY W. HERSHLEY.
